A. G. WETTERGREN & R. L. TREFFURTH.

EXTENSION TABLE.

(Application filed Aug. 5, 1898.)

(No Model.)

UNITED STATES PATENT OFFICE.

ADDICK GEORGE WETTERGREN AND RICHARD L. TREFFURTH, OF
NEW YORK, N. Y.

EXTENSION-TABLE.

SPECIFICATION forming part of Letters Patent No. 622,578, dated April 4, 1899.

Application filed August 5, 1898. Serial No. 687,780. (No model.)

To all whom it may concern:

Be it known that we, ADDICK GEORGE WETTERGREN and RICHARD L. TREFFURTH, citizens of the United States, residing at Manhattan borough, New York city, in the county of New York and State of New York, have invented certain new and useful Improvements in Extension-Tables; and we do hereby declare the following to be a full, clear, and exact description of the invention, such as will enable others skilled in the art to which it appertains to make and use the same.

Our invention refers to an extension-table, the object being to easily convert a small bedroom table into a dining-table; and the invention therefore consists in the construction and combinations of parts, substantially as will be hereinafter described and claimed.

In the annexed drawings, illustrating our invention, Figure 1 is a perspective view of our improved table before being extended, its form after extension being shown in dotted lines. Fig. 2 is a longitudinal section of the same. Fig. 3 is a longitudinal section of the table when extended. Fig. 4 is a cross-section. Fig. 5 is an enlarged detail view showing one of the locking-bolts. Fig. 6 is a detail perspective view of the tongue-and-grooved device at one end of the table-cover. Fig. 7 is a cross-section of the same.

Like numerals of reference denote like parts in all the figures.

2 denotes the body of a table, made hollow to provide a longitudinal compartment and having the usual legs 3, said body 2 being normally covered by the table-top 1, which is a single flat piece. The common appearance of the unextended table is shown in Fig. 1 in full lines. The top 1 is adapted to be slid endwise for a certain distance when an extension of the table is to be effected. The inner opposing faces of the longitudinal sides of the body 2 are formed for a certain distance from one end of said body with grooves or channels 6, which receive the opposite sliding ends of a transverse slide 5, that is pivoted at its center to the under side of top 1 by means of a pin 7, rigidly secured to top 1 and passing through the strip 5, its lower end having a retaining-pin 8. After the top 1 has been slid endwise for a convenient dis-

tance it will be rotated upon the pin 7 through an arc of one-quarter of a circle, which will place said top transversely across one end portion of the body 2, leaving a portion of the compartment in said body 2 uncovered and exposed, and through this opening the hinged and folded leaf 4, which is kept in the body 2 when not needed for use, may be withdrawn, unfolded, and laid alongside of the cover 1 across the other end portion of the table-body, thus completing the extension of the table and providing a table of twice the size of the original one. When the top 1 is in its accustomed position upon the body 2, 65 the tongue-pieces 10, a pair of which are secured to the under face of said cover at one of its end edges, will engage the sockets 9, that are set into the body of the table or the upper ends of the legs 3, as shown in Fig. 70 6, the same being flush with the upper surface of said body, so as to leave no projecting points. Also this end of the top 1 is secured to the body 2 by means of some suitable catch or lock devices, of which we preferably employ two, although we may use any number, and a preferred form of lock device that we employ we have illustrated in the drawings as an example, and we will now proceed to describe it. The detailed construction 80 of one of these lock devices is delineated in Figs. 4 and 5. On the upper edge of the end piece of body 2 is secured a flat plate 16, having a transverse slot therein. Beneath it on the inner face of said end piece is secured a 85 vertical strip 23, having an integral laterally-grooved projecting block 13, and in engagement with this block is a vertically-sliding slotted strip 14, having a slot through which the block 13 projects and having also at its 90 upper end another slot 15. Tensioned between the stationary block 13 and the lower end of the sliding strip 14 is a spring 20, the effect of which is to normally force the strip 14 downward, so that its upper tip end will 95 be below or flush with the horizontal plate 16. The strip 14 may be readily manipulated, however, to lift it upward through the slotted plate 16, so that the slotted end 15 will be above plate 16. Within a recess in the cover 100 1 is a spring-bolt consisting of a bolt proper, 16, having a finger end 11 and supported in

- bearings, together with a spring 12 for forcing the bolt 10 endwise for the purpose of causing it to engage the slot 15 in the end of strip 14 when the latter is lifted, thus locking 5 the cover 1 to the body 2. By drawing the bolt 10 endwise in the other direction the bolt can be disengaged from strip 14, which will fly downward under the impulse of spring 20. As we have stated, we preferably use two 10 of these catch devices on the end of top 1. We also provide the folded leaf 4 with a couple of them, which operate at the opposite end of the table, after the leaf 4 has been placed across the body, to hold the latter in position. 15 The leaf 4 preferably has the pins 21 21, that take under the edge of top 1 to keep the adjoining edges of the two leaves close together. Also top 1 has a stop 22 to limit its rotary movement. 20 What we claim is—
1. In an extension-table, the combination with the body having a leaf-receiving compartment and having also longitudinal side grooves in the interior of the body, of the 25 table-top, a pivotal transverse bar carried on the under side of said top with its ends entering and slidably within the aforesaid grooves

in the body, so that the said top may be moved endwise and then rotated into a position at right angles to the body, as set forth, a plurality of tongue-pieces secured to the under surface of the cover, sockets formed in the table-body to receive said tongue-pieces, and the hinged extension-leaf for completing the table after the pivotal leaf has been rotated, 35 substantially as described.

2. In an extension-table, the combination with the body, of a slidable and rotatable top, a hinged folding extension-leaf, and locking devices, consisting of slotted plates supported and working upon blocks upon the table-frame, springs to normally hold said slotted plates retracted, and spring-actuated bolts supported upon the table-leaf and adapted to engage perforations in the slotted plates 40 and lock the cover upon the body, substantially as described.

In testimony whereof we affix our signatures in presence of two witnesses.

ADDICK GEORGE WETTERGREEN.
RICHARD L. TREFFURTH.
